SHOCK ABSORBER EQUIPMENT FOR KNITTING MACHINES

Max Richter, West Reading, Pa., assignor to Textile Machine Works, Wyomissing, Pa., a corporation of Pennsylvania

Application February 24, 1937, Serial No. 127,364

15 Claims. (Cl. 66—130)

This invention relates to novel mechanism for selectively controlling the operation of shock-absorbing means for knitting machines and particularly to means associated with full-fashioned stocking and other straight knitting machines to cause a mechanism for absorbing or reducing the shock impact of a yarn carrier bar with its end stops to be rendered active or inactive according to a pattern.

10 It has heretofore been suggested to provide means for reducing or absorbing the shocks of impact between the yarn-carrier bars and the end stops of a full-fashioned knitting machine. Such shocks have adverse effects in the operation 15 of the machine by causing vibrations tending to wear and loosen parts, causing unnecessary noise and sometimes having deleterious effects on the fabric.

For reducing the shocks, a suggested mechanism comprises a rod which is disposed parallel to the actuator or friction rod means and moves in the same direction as the friction rod at the same time, but at a speed reduced relative to the main carrier speed. An element on a friction box operates between two elements on the shock reducing rod such that, as the friction rod approaches the ends of its strokes, the element on the box overtakes, and is intercepted by, one of the elements on the reduced-speed rod, whereby the speed of the friction box is reduced before the carrier bar hits its end stops.

In the operation of a full-fashioned stocking machine, where it is desired to have a carrier that has laid full-width yarns in the leg area of a blank also lay partial courses in a heel tab, it has been the practice to stop the machine, for manually rendering inoperative the shock reducer means associated with the friction box of such carrier.

40 In running idle courses, the friction boxes are stopped, while remaining portions of the machine go through the motions of knitting without producing fabric. Thus, if the above-mentioned elements on the friction boxes for interception by the elements on the shock-reducing rod are allowed to remain in active position while running an idle course, collision between the elements on the boxes and on the speed-reducing rod will result in damage to these elements.

50 An object of the invention is to avoid the above-mentioned disadvantages and to ensure proper operation of the machine by having the shock-reducer elements in active relation during the times of knitting full-width courses and in inactive relation during the times of knitting heel tab areas and of running idle courses. The results are attained in response to operation of the machine in accordance with the change in pattern between the leg and the heel tabs whereby manual manipulation and attendant disadvantages thereof, such as imperfect operation and having to stop the machine, are avoided.

Another object of the invention is to effect the above-mentioned pattern control of the shock absorbing or reducing means in a simple, 5 effective and economical manner, whereby the speed of production is increased, the likelihood of disorders of the machine and defects in the knitted blank is substantially reduced, the hazards of manual control are eliminated and other 10 advantages are attained.

With the above and other objects in view, which will become apparent from the following description of the illustrative embodiment of the invention shown in the accompanying drawings, 15 the invention comprises the novel elements, mechanisms, features of construction and combination of parts in cooperative relation, as hereinafter particularly pointed out in the claims.

In the drawings:

Figure 1 is a rear elevational view on a reduced scale of a portion of a full-fashioned knitting machine embodying the invention;

Fig. 2 is a vertical cross-sectional view, on a slightly enlarged scale, of the machine shown in Fig. 1, taken substantially along the line 2—2;

Fig. 3 is a view similar to Fig. 2, parts being omitted for clearness;

Fig. 4 is an enlarged detail view, partially in elevation and partially in section, of a shock-absorber device located at the upper left center of Fig. 1;

Fig. 5 is a view taken substantially along the line 5—5 of Fig. 4;

Figs. 6 and 7 are views, similar to the bottom portion of Fig. 4, showing the parts thereof in different operative positions;

Fig. 8 is an enlarged detail view of portions of the machine as viewed at the upper left-hand portion of Fig. 3, showing the parts thereof 40 in different operative positions;

Fig. 9 is a view taken substantially along the line 9—9 of Fig. 8;

Fig. 10 is an enlarged sectional detail view, taken substantially along the line 10—10 of Fig. 8; and

Fig. 11 is a diagram of a full-fashioned stocking leg blank, together with a diagram showing the development of a pattern chain along a straight line in side elevation from its normal 50 loop shape indicating the positions along the blank at which the shock-reducing means is rendered effective and ineffective.

The figures disclose various parts of a "Reading" full-fashioned stocking-knitting machine 55 embodying the invention in which for clearness only the parts necessary to an understanding of the invention are illustrated. The other parts and the operation thereof are well known in the art, as shown and described in the "Reading" 60

Full Fashioned Knitting Machine Catalogues, copyright 1920, 1929 and 1935 and published by the Textile Machine Works, Reading, Pennsylvania, and in a booklet entitled "Knitting Machine Lectures", published in 1935 by the Wyomissing Polytechnic Institute, Wyomissing, Pennsylvania.

In a machine of the type illustrated, end and center frames 10, Figs. 1, 2 and 3, are rigidly held in parallel spaced relation by members including a front beam 12, a back beam 13 and a center bed 14, which together constitute a base frame on which the operating parts are supported.

A couliering mechanism 11, Fig. 1, of a well known type, comprises a draw arm or pitman 15 on which is adjustably mounted a pair of rollers 16, only one of which is shown, for coaction with a coulier cam 17 to oscillate with a small rocker arm, not shown, and a large rocker arm 19. The couliering mechanism operates to translate the rotational movement of a cam shaft 21 into the reciprocative movement of the yarn-feeding mechanism.

The rocker arms are pivotally connected to mountings by studs, such as the mounting 24 and the stud 26 associated with the long arm 19. The mountings are secured to the top and under sides, respectively, of the back beam 13.

Reciprocation of the draw bar 15 oscillates the large rocker arm 19 about its pivot stud 26 and reciprocates a cross-head 27, through a connector element or link 28, the ends of which are pivoted to the rocker arm 19 and to the cross-head 27, respectively, by studs 29 and 30. Operation of the cross-head 27 and of a friction rod 32 secured thereto, operates a friction box 34 on the rod 32.

The mechanism above set forth, which is well known in the art and is embodied in a full-fashioned machine of the type shown in the "Reading" catalogue, is included herein for an understanding of the invention, which cooperates with this mechanism to reduce the speed of the carriers as they approach the end stops. This feature operates to substantially reduce the shock of impact between the carrier bar and its end stops.

A carrier-bar speed-reducing for auxiliary rod 43 is longitudinally slidably supported by bearings in brackets 41 carried by a center frame 10 and 50 is reciprocated at a reduced rate of speed relative to the actuator or friction rod 32 by a device 44 comprising a base support including a two-part bracket, including upper and lower members 45 and 46, respectively. The member 45 supports 55 an auxiliary shock absorber 42, Figs. 1, 4, 5, 6 and 7, including a plunger 48, which is held by a compression spring 49 in yielding engagement with a thickened portion of the rod 43 in a notch 58. The spring 49 impinges against a member 50 60 adjustably bridged between bolts 52 by nuts 53.

The device 44 is slidably mounted on a back narrowing shaft 54 and is reciprocated by the large rocker arm 19 through a link 55. The ends of the link 55 are pivotally mounted on studs 56 and 57 carried by the arm 19 and the bracket 46, respectively. The stud 56 is preferably normally disposed half way between the studs 26 and 29 whereby to move at half the rate of speed at which the stud 29 oscillates. Consequently, the device 44 and the rod 43 yieldingly secured thereto through the plunger 48 and the notch 58 in the positions of the parts of Figs. 4 and 5, are reciprocated at half the rate of speed at which the cross-head 27 and the friction rod 32 operate. 70 This rate may be adjustably varied by changing

the positions of the studs 56 and 57 in vertical slots in the rocker arm 19 and the bracket member 46, respectively.

Referring to Figs. 2 and 3, yarn carriers 62 mounted on reciprocable carrier bars 4 to 8, respectively, are operated by the friction boxes of the machine to feed the yarns to needles 63. The needles are clamped to a needle bar 64, which is actuated by needle and presser levers 65 and 66 operated by cams on the cam shaft 21. Sinkers 10 72 and dividers 73 cooperate with the needles 63 to form loops.

The forward movement of the sinkers 72 is effected by a reciprocable cock box assembly 75 through jacks 74. The forward movement of the dividers 73 and the retraction movement of the sinkers 72 and the dividers 73 are effected by cams on the cam shaft 21. This movement is transmitted to a catch bar 77 through a linkage including a cam follower 78, a cam lever 79, a horizontal catch bar shifter 82 and a vertical shifter arm 83.

An auxiliary pattern unit includes a control shaft 86, Figs. 2, 3, 8 and 9, supported by bearing members 87 attached to a bar 88, which is secured to the center frames 10. The shaft 86 is intermittently racked by a cam 89 when a lever 92, pivotally mounted on the front beam 12 by a pin 93, is operated by actuation of a rod 94. This movement of the rod 94 is effected by a button 30 mounted on an auxiliary chain which is attached to, and operated by, the main chain-motion mechanism.

Removal of the lever 92 from beneath the horizontal arm of a bell crank 98 permits a fol- 35 lower 99 to move in accordance with the contour of the cam 89, whereupon rotation of the shaft 86 is caused by the intermittent movement of a ratchet wheel 102 secured thereto. The ratchet wheel 102 is actuated by a pawl 103 that is pivotally mounted on a member 104, which is rotatably mounted on the shaft 86 and connected by a link 105 to the upper end of the bell crank 98.

A spring 106 is secured at one end to the back beam 13 by a bracket 107 and has its opposite end connected to a hook portion of the link 105, thereby providing means for holding the cam follower 99 in yielding engagement with the cam 89 when the lever 92 disengages the lever 98. A detent 109, pivotally mounted on a pin 112, is held in yielding engagement with the teeth of the ratchet wheel 102 by a spring 114 to prevent reverse movement of the control shaft as viewed in Fig. 2.

An auxiliary pattern-unit control chain 115 is mounted at one end on a sprocket wheel 116 that is secured to the shaft 86 and at the other end by an idler sprocket wheel that is supported by a bracket 118, Fig. 1, on the bar 88 at the rear of the machine. A similar chain 122 is also carried by sprocket wheels on the shaft 86 and the bar 88 for operating a selective three-carrier mechanism 123 of the friction box 34.

A roller follower 125 for cooperation with the chain 115 is rotatably mounted on a lever 126 that has a pivotal mounting 127 on a bracket 128 secured to the bar 88. A spring 129 biases the lever 126 clockwise, as viewed in Figs. 2, 3 and 8, to cause the roller 125 to follow the contour of the chain 115, which, as shown, has high links 115a and low links 115b.

A pattern responsive means or member 132, pivoted to the upper end of the bracket 128, by a pin 133, has a slot 134 and two arms 135 and 136, to which are detachably secured jaw members 137 and 138, respectively. These jaws ex- 75

tend parallel to the friction rod 32 and have divergently flared ends 142 and 143, respectively, Fig. 9. A pin 144 is adjustably secured to the member 132 in the slot 134 for cooperation with a bifurcate upper end 145 of the lever 126, so that, when the lever 126 is turned about its pivot 127, the member 132 is oppositely pivoted about its pivot 133.

A lever arm or member 146 pivotally mounted on the friction box 34 by a pin 147 has its outer or free end 148, Fig. 9, tapered from the center of the lever oppositely in the direction of the friction rod so that, at a position of a carrier corresponding to the end of a full-course stroke as in the leg of a stocking, the end 148 will lie between the jaws 137 and 138. As more clearly seen in Fig. 9, entrance of the lever to position between the jaws 137 and 138 at the left hand end of the stroke of the friction box on which the lever is mounted, is facilitated by the flared ends 142 and 143 of the jaws and by the taper of the end 148 of the lever 146. This feature ensures proper positioning of the lever between the jaws at the end of the stroke in case the lever is manually or otherwise moved from such position while the machine is idle and the lever 146 is spaced from the jaws at an intermediate position of its stroke.

As shown in Figs. 1 and 3, the lever 146 is in a lower position projecting laterally from the friction box 34 wherein, near each end of its stroke, it is intercepted by one of a pair of elements 155 between which it is located and which are fixed to the shock rod 43. Since this rod travels in the same direction as the friction box, but at half the speed of the box, when the lever 146 engages the element 155 intercepting its path in this direction, the speed of the box is reduced from the time of interception of the lever by the element until the carrier bar being moved by the box is engaged by its end stop. This action renders engagement of the carrier bar with the stop free from undesirable shock.

At each interception of the lever 146 by one of the elements 155, the auxiliary shock absorber device 42 allows momentary play between the rod 43 and its drive by slight movement of the plunger 48 out of the notch 58, as indicated in Fig. 6, thus compressing the spring 49 and absorbing some of the forces of the impact. In case the rod 43 is stopped or opposed by an abnormal force greater than necessary to move the plunger 48 out of the notch 58 at an intermediate position of the friction-rod stroke, the plunger 48 will move entirely out of the notch, as indicated in Fig. 7, thus preventing damage to parts.

Lateral bend of the lever 146 while it is engaging one of the elements 155, is prevented by having the lever reinforced along its sides by portions 152 of the friction box, which form a groove 154 in which the lever is disposed, Fig. 10. As also shown in this figure, the lever 146 is provided with a side notch 167 for cooperation with a detent device on the friction box comprising a ball 168, a spring 169, and an adjustable screw and nut device 172 for holding the ball and the spring. This device is for holding the lever 146 in its upper position, indicated in Fig. 8, in which the lever 146 clears or is out of the path of the adjacent element 155 when a carrier rod connected to the box is operating through a short stroke, as in the heel tab of a stocking. For this operation, the lever 146 is lifted by the jaws 137-138 from its position of Fig. 2 to its position of Fig. 8.

Lifting of the jaws 137-138 is accomplished according to the pattern of the stocking blank being knitted when the low links 115b of the chain 115 are moved to position opposite the follower 125 and the chain is moved by racking of the 5 ratchet wheel 102 by the pawl 103 to turn the shaft 86. When the rod 94 is moved longitudinally by a button of the main chain motion mechanism, the lever 92 is moved from beneath the bell crank 98 so that the roller 99 may follow the contour of the cam 89, which action causes intermittent reciprocation of the link 105 and corresponding racking of the ratchet wheel 102.

In the particular example illustrated, the friction box 34 is of a special type whereby it may at 15 the end of each stroke be detached from one of a set of three carrier bars and attached to another bar of the set to operate these bars for laying three separate yarns of like gauge, color and kind 20 in repeated succession to avoid rings or shadows. The friction box may also be attached to a carrier bar, other than the three bars operated in repeated succession, such as the bar for laying yarn to the welt.

In this instance, the carriers attached to the bars 4, 2 and 1 are selected to lay the courses of the ringless area between courses 170 and 171, as indicated in Fig. 11. The blank is knitted from the first course 174 in the welt W to the selected course 170 below the welt line 175 from a yarn laid by the carrier of the bar 3 connected to the friction box 34, at which position the carrier of the bar 3 is disconnected from the box 34 and is laid out of operation, and the three carriers for repeated succession placed in operation. At the tops 176 of the upper heel areas, the three thread carriers are augmented, in the left upper heel area, as viewed in Fig. 11, by the carrier of carrier bar 8 and, in the right upper heel area by the carrier of the bar 7. This action continues to within two or three courses of the course 171, where the carrier bars 2 and 1 are disconnected from the friction box 34 and the carrier bar 4 is allowed to remain attached to the box. The bar 1 is thrown out of operation entirely, but the bar 2 is taken up by another friction box and operated to lay yarn in the left heel tab. The box 34, although being constructed specially to translate the motion of the three thread carrier bars 4, 2 and 1, is thus operable to lay the single yarn by 50 the carrier bar 4 in the left heel tab, while the carrier bar 8 attached to a separate friction box is also laying yarn in the left heel tab, Fig. 11. In the right heel tab, the carrier bar 2, previously disconnected from the three carrier friction box 34, is operated by a separate friction box, along with the carrier bar 7, which is operated by a corresponding separate box.

As indicated in Fig. 11, the machine has idle movement for a distance from a line 177, at the top of the figure representing the position of the last course of the heel tabs of a previously knitted blank, to the first course 174 of the next subsequent blank illustrated, at which time the follower 125 is still on one of a set of the low links 115b. At the course 174, the high links 115a move to position opposite the follower 125 which is thereby actuated to move the lever 146 to its lower position, in which it is intercepted by the elements 155-156 on the half-speed shock absorber rod 43. The lever 146 remains in its lowered position from the course 174 to the course 176 where the low links 115b move to position opposite the follower 125, thereby moving the lever 146 out of 70 75

the path of the elements 155 until the course 174 is started in the next subsequent blank.

- The action whereby the friction box 34 changes from its operation in carrying the carrier bar 3 to its three-carrier operation carrying the bars 4, 2 and 1, then again returns to its single carrier operation, carrying the bar 4, and finally changes back again to the carrier bar 3, is effected in a manner not specifically generic to this invention, but generally effected by a lever 178, Fig. 1, which is controlled by the chain 122, having high, intermediate and low links operable by the auxiliary control shaft 86 in a manner similar to that above-described with respect to the chain 115. The three-carrier attachment 123 on the friction box 34 has pointed elements 181 and 182 projecting oppositely along the friction rod for cooperation, respectively, with a socket member 183 on the movable arm 178 and a stationary socket member 184. Normally, during the knitting of the three-thread area, the socket member 183 is also stationary in line with the elements 181 and 182 and with the stationary socket 184. At the ends of the friction box strokes, the pointed elements 181 and 182 enter the socket members 183 and 184 merely for a precautionary position maintaining effect on parts of the friction box which might otherwise become displaced from the action of the machine. Bodily movement of the socket 183 laterally of the friction rod by the chain 122 when the element 181 is in the socket, disrupts the three-carrier operation and institutes the single carrier operation of the friction box 34, as above mentioned.
- The carrier bar 4 in the above-described operation, thus impacts one of its end stops at the corresponding end of every stroke throughout the production of the blank from the course 170 to the course 171, as shown at the bottom of Fig. 11. The bar 4 does this at the ends of full strokes from the course 170 to the course 171 and at the ends of partial strokes from the course 171 to the bottom course 177. With the arm 146 in its lower position during the full strokes to be intercepted by the elements 155 and in its upper position to avoid interception by these elements and this change being controlled by the pattern mechanism in accordance with the shape of the stocking blank, means is thus provided, responsive to operation of the machine, for selectively reducing or avoiding the reduction of the shock of impact of the carrier bar 4 at one end of its stroke in accordance with such pattern or shape and provision is made for varying the shock reducing effect by varying the relation of the speed of the rod 43 to that of the friction rod 32, and by adjusting the spring 49.
- Although a particular form of the invention has been shown and described, changes may be effected therein without departing from the spirit and scope thereof, as set forth in the appended claims.
- I claim:
1. In a straight knitting machine, a carrier bar, a friction rod, a friction box, an auxiliary rod parallel to the carrier bar and the friction rod, elements spaced along the auxiliary rod carried thereby, a member on the friction box, means for longitudinally reciprocating the friction rod at any of a selection of speeds and the auxiliary rod simultaneously in the same directions at a proportionately lesser speed, pattern responsive means for moving said member relative to the friction box at a location between said elements selectively between a position in the

path of movement of said elements and a position out of said path whereby when said member is in said first position it is adapted to engage one of said elements for retardation thereby to reduce the speed of the friction box for part of its stroke to the speed of said auxiliary rod and when said member is in said second position it will avoid engaging said elements and the speed of the friction box will be maintained throughout its stroke, and pattern means controlling said pattern responsive means to move said member to said first position at a predetermined high speed of the friction rod and to said second position at a predetermined low speed of the friction rod.

2. In a straight knitting machine, a carrier bar, a friction rod, a friction box, an auxiliary rod parallel to the carrier bar and the friction rod, elements spaced along the auxiliary rod carried thereby, a member on the friction box, means for longitudinally reciprocating the friction rod at any of a selection of speeds and the auxiliary rod simultaneously in the same directions at a proportionately lesser speed, means yieldably connecting said auxiliary rod to said rod reciprocating means, pattern responsive means for moving said member relative to the friction box at a location between said elements selectively between a position in the path of movement of said elements and a position out of said path whereby when said member is in said first position it is adapted to engage one of said elements for retardation thereby to reduce the speed of the friction box for part of its stroke to the speed of said auxiliary rod and when said member is in said second position it will avoid engaging said elements and the speed of the friction box will be maintained throughout its stroke, and pattern means controlling said pattern responsive means to move said member to said first position at a predetermined high speed of the friction rod and to said second position at a predetermined low speed of the friction rod.

3. In a straight knitting machine, a carrier bar, a friction rod, a friction box, an auxiliary rod parallel to the carrier bar and the friction rod, elements spaced along the auxiliary rod carried thereby, a member on the friction box, means for longitudinally reciprocating the friction rod at any of a selection of speeds and the auxiliary rod simultaneously in the same directions at a proportionately lesser speed, means yieldably connecting said auxiliary rod to said rod reciprocating means, means for adjusting the degree of yieldability of said connecting means, pattern responsive means for moving said member relative to the friction box at a location between said elements selectively between a position in the path of movement of said elements and a position out of said path whereby when said member is in said first position it is adapted to engage one of said elements for retardation thereby to reduce the speed of the friction box for part of its stroke to the speed of said auxiliary rod and when said member is in said second position it will avoid engaging said elements and the speed of the friction box will be maintained throughout its stroke, and pattern means controlling said pattern responsive means to move said member to said first position at a predetermined high speed of the friction rod and to said second position at a predetermined low speed of the friction rod.

4. In a straight knitting machine, a carrier bar, a friction rod, a friction box, an auxiliary rod

parallel to the carrier bar and the friction rod, elements spaced along the auxiliary rod carried thereby, a member on the friction box, means for longitudinally reciprocating the friction rod at any of a selection of speeds and the auxiliary rod simultaneously in the same directions at a proportionately lesser speed, means yieldably connecting said auxiliary rod to said rod reciprocating means, pattern responsive means for moving said member relative to the friction box at a location between said elements selectively between a position in the path of movement of said elements and a position out of said path whereby when said member is in said first position it is adapted to engage one of said elements for retardation thereby to reduce the speed of the friction box for part of its stroke to the speed of said auxiliary rod and when said member is in said second position it will avoid engaging said elements and the speed of the friction box will be maintained throughout its stroke, said yieldable connecting means being adapted to yield at each engagement of said member with one of said elements and to return to initial connecting position after such engagement, and pattern means controlling said pattern responsive means to move said member to said first position at a predetermined high speed of the friction rod and to said second position at a predetermined low speed of the friction rod.

5. In a straight knitting machine, a carrier bar, a friction rod, a friction box, an auxiliary rod parallel to the carrier bar and the friction rod, elements spaced along the auxiliary rod carried thereby, a member on the friction box, means for longitudinally reciprocating the friction rod at any of a selection of speeds and the auxiliary rod simultaneously in the same directions at a proportionately lesser speed, pattern responsive means for moving said member relative to the friction box at a location between said elements selectively between a position in the path of movement of said elements and a position out of said path whereby when said member is in said first position it is adapted to engage one of said elements for retardation thereby to reduce the speed of the friction box for part of its stroke to the speed of said auxiliary rod and when said member is in said second position it will avoid engaging said elements and the speed of the friction box will be maintained throughout its stroke, said pattern responsive means being adapted for operative connection to said member only at a given position of the friction box, and pattern means controlling said pattern responsive means to move said member to said first position at a predetermined high speed of the friction rod and to said second position at a predetermined low speed of the friction rod.

6. In a straight knitting machine, a carrier bar, a friction rod, a friction box, an auxiliary rod parallel to the carrier bar and the friction rod, elements spaced along the auxiliary rod carried thereby, means for longitudinally reciprocating the friction rod at any of a selection of speeds and the auxiliary rod simultaneously in the same directions at a proportionately lesser speed, a lever pivotally mounted on the friction box about an axis parallel to said rods and projecting laterally from the box, pattern responsive means for pivotally moving said lever at a location between said elements selectively between a position in the path of movement of said elements and a position out of said path whereby when said member is in said first position it is adapted to

engage one of said elements for retardation thereby to reduce the speed of the friction box for part of its stroke to the speed of said auxiliary rod and when said lever is in said second position it will avoid engaging said elements and the speed of the friction box will be maintained throughout its stroke, means for bracing said lever between its pivot and free ends against the side thrust of said elements, and pattern means controlling said pattern responsive means to move said lever to said first position at a predetermined high speed of the friction rod and to said second position at a predetermined low speed of the friction rod.

7. In a straight knitting machine, a carrier bar, a friction rod, a friction box, an auxiliary rod parallel to the carrier bar and the friction rod, elements spaced along the auxiliary rod carried thereby, means for longitudinally reciprocating the friction rod at any of a selection of speeds and the auxiliary rod simultaneously in the same directions at a proportionately lesser speed, a lever pivotally mounted on the friction box about an axis parallel to said rods and projecting laterally from the box, pattern responsive means for pivotally moving said lever at a location between said elements selectively between a position in the path of movement of said elements and a position out of said path whereby when said lever is in said first position it is adapted to engage one of said elements for retardation thereby to reduce the speed of the friction box for part of its stroke to the speed of said auxiliary rod and when said lever is in said second position it will avoid engaging said elements and the speed of the friction box will be maintained throughout its stroke, means for holding the lever in said second position independently of said pattern responsive means, and pattern means controlling said pattern responsive means to move said lever to said first position at a predetermined high speed of the friction rod and to said second position at a predetermined low speed of the friction rod.

8. In a straight knitting machine, a carrier bar, a friction rod, a friction box, an auxiliary rod parallel to the carrier bar and the friction rod, elements spaced along the auxiliary rod carried thereby, a member on the friction box, means for longitudinally reciprocating the friction rod at any of a selection of speeds and the auxiliary rod simultaneously in the same directions at a proportionately lesser speed, means for regulating the speed of the auxiliary rod relative to the speed of the friction rod, pattern responsive means for moving said member relative to the friction box at a location between said elements selectively between a position in the path of movement of said elements and a position out of said path whereby when said member is in said first position it is adapted to engage one of said elements for retardation thereby to reduce the speed of the friction box for part of its stroke to the speed of said auxiliary rod and when said member is in said second position it will avoid engaging said elements and the speed of the friction box will be maintained throughout its stroke, and pattern means controlling said pattern responsive means to move said member to said first position at a predetermined high speed of the friction rod and to said second position at a predetermined low speed of the friction rod.

9. In a full-fashioned knitting machine, a carrier bar, a friction box, an auxiliary rod parallel to the carrier bar and the friction rod, elements

- spaced along, and secured to, the auxiliary rod, a lever pivoted to the friction box, means for actuating the friction rod at a given speed and the auxiliary rod at a predetermined lesser speed, and means responsive to operation of the machine for moving said lever about its pivot selectively between a position intermediate, and in the path of movement of, said elements and a position aside said path including a main pattern unit, and an auxiliary pattern-control unit comprising a shaft, a sprocket wheel on the shaft, a pattern chain on the sprocket wheel, a pivotally mounted member for moving said friction-box lever, and a follower for said chain cooperating with said pivotal member.
10. In a full-fashioned knitting machine, a carrier bar, a friction box, an auxiliary rod parallel to the carrier bar and the friction rod, elements spaced along, and secured to, the auxiliary rod, a lever pivoted to the friction box, means for actuating the friction rod at a given speed and the auxiliary rod at a predetermined lesser speed, and means responsive to operation of the machine for moving said lever about its pivot selectively between a position intermediate, and in the path of movement of, said elements and a position aside said path including a main pattern unit, and an auxiliary pattern-control unit comprising a shaft, a sprocket wheel on the shaft, a pattern chain on the sprocket wheel, a pivotally mounted member for moving said friction-box lever, a second pivotally mounted lever for actuating said pivotally mounted member, and a follower for said chain carried by said second lever.
15. 11. In a full-fashioned knitting machine, a carrier bar, a friction box, an auxiliary rod parallel to the carrier bar and the friction rod, elements spaced along, and secured to, the auxiliary rod, a lever pivoted to the friction box, means for actuating the friction rod at a given speed and the auxiliary rod at a predetermined lesser speed, and means responsive to operation of the machine for moving said lever about its pivot selectively between a position intermediate, and in the path of movement of, said elements and a position aside said path including a main pattern unit, and an auxiliary pattern-control unit comprising a shaft, a sprocket wheel on the shaft, a pattern chain on the sprocket wheel, a pivotally mounted member for moving said friction-box lever, said member embodying a pair of jaws opening in the direction of the friction rod for receiving said lever between the jaws, a second pivotally mounted lever for actuating said pivotal member, and a follower for said chain carried by said second lever.
20. 12. In a full-fashioned knitting machine, a carrier bar, a friction box, an auxiliary rod parallel to the carrier bar and the friction rod, elements spaced along, and secured to, the auxiliary rod, a lever pivoted to the friction box, means for actuating the friction rod at a given speed and the auxiliary rod at a predetermined lesser speed, and means responsive to operation of the machine for moving said lever about its pivot selectively between a position intermediate, and in the path of movement of, said elements and a position aside said path including a main pattern unit, and an auxiliary pattern-control unit comprising a shaft, a sprocket wheel on the shaft, a pattern chain on the sprocket wheel, a pivotally mounted member for moving said friction-box lever, a pin car-

ried by said pivotally-mounted member, a second pivotally mounted lever having a bifurcated end embracing said pin for actuating said pivotal member, and a follower for said chain carried by said second lever.

13. In a full-fashioned knitting machine, a carrier bar, a friction box, an auxiliary rod parallel to the carrier bar and the friction rod, elements spaced along, and secured to, the auxiliary rod, a lever pivoted to the friction box, means for actuating the friction rod at a given speed and the auxiliary rod at a predetermined lesser speed, and means responsive to operation of the machine for moving said lever about its pivot selectively between a position intermediate, and in the path of movement of, said elements and a position aside said path including a main pattern unit, and an auxiliary pattern-control unit comprising a shaft, a sprocket wheel on the shaft, a pattern chain on the sprocket wheel, a pivotally mounted member for moving said friction-box lever, a pin carried by said pivotally-mounted member and adapted for adjustment to any one of different positions thereon, a second pivotally mounted lever having a bifurcate end embracing said pin for actuating said pivotal member, and a follower for said chain carried by said second lever.

14. In a full-fashioned knitting machine, a carrier bar, a friction box, an auxiliary rod parallel to the carrier bar and the friction rod, elements spaced along, and secured to, the auxiliary rod, a lever pivoted to the friction box, means for actuating the friction rod at a given speed and the auxiliary rod at a predetermined lesser speed, and means responsive to operation of the machine for moving said lever about its pivot selectively between a position intermediate, and in the path of movement of, said elements and a position aside said path including a main pattern unit, and an auxiliary pattern-control unit comprising a shaft, a sprocket wheel on the shaft, a pattern chain on the sprocket wheel, a pivotally mounted member for moving said friction-box lever, a follower for said chain for cooperation with said pivotal member, and means operative upon removal of the chain from the sprocket wheel for limiting movement of the follower toward the wheel.

15. In a full-fashioned knitting machine, a carrier bar, a friction box, an auxiliary rod parallel to the carrier bar and the friction rod, elements spaced along, and secured to, the auxiliary rod, a lever pivoted to the friction box, means for actuating the friction rod at a given speed and the auxiliary rod at a predetermined lesser speed, and means responsive to operation of the machine for moving said lever about its pivot selectively between a position intermediate, and in the path of movement of, said elements and a position aside said path including a main pattern unit, and an auxiliary pattern-control unit comprising a shaft, a sprocket wheel on the shaft, a pattern chain on the sprocket wheel, a pivotally mounted member for moving said friction-box lever, said member embodying a pair of jaws detachably secured thereto for receiving said lever between the jaws, a second pivotally-mounted lever for actuating said pivotal member, and a follower for the chain carried by the second lever.
